UNITED STATES PATENT OFFICE.

MILES A. HANSON, OF PORT WASHINGTON, WISCONSIN.

DESIGN FOR A CHAIR-LEG.

SPECIFICATION forming part of Design No. 25,255, dated March 17, 1896.

Application filed December 11, 1895. Serial No. 571,833. Term of patent 14 years.

To all whom it may concern:

Be it known that I, MILES A. HANSON, of Port Washington, in the county of Ozaukee and State of Wisconsin, have invented a new 5 and original Design for a Chair-Leg, of which the following is a description, reference being had to the accompanying drawings, which form a part of this specification.

Figure 1 is an elevation of a chair-leg illustrating my invention, and Fig. 2 is a plan view of the leg.

The leading feature of my design is the general shape and form of a chair-leg, as herein shown and described, whereby a graceful and 15 ornamental effect is produced.

The letter A indicates a chair-leg embodying my design which longitudinally is of a sigmoidal form or shape, the lower curve being upward and the upper curve downward,

said upper curve merging into a straight vertically-extending extremity. It will also be noticed that the leg has its greatest width at the top, and that this width gradually tapers to the lower end, which point therefore is the narrowest portion of the leg. At its upper 20 straight extremity the leg is shaped to form an upwardly-projecting tongue B, and at the base of this tongue is an outer shoulder, C, and two side shoulders, D D.

What I claim is—

The design for a chair-leg as herein shown and described.

In testimony whereof I affix my signature in presence of two witnesses.

MILES A. HANSON.
